US00D986196S

(12) **United States Design Patent** (10) **Patent No.:** **US D986,196 S**
Brutler et al. (45) **Date of Patent:** **** May 16, 2023**

(54) **COMMUNICATION MODULE**

(71) Applicant: **Gentex Corporation**, Simpson, PA (US)
(72) Inventors: **Zoltan S. Brutler**, Groton, MA (US); **Michael Pearson Blundell**, Windham, NH (US)

(73) Assignee: **Gentex Corporation**, Simpson, PA (US)

(**) Term: **15 Years**

(21) Appl. No.: **29/740,165**

(22) Filed: **Jul. 1, 2020**

Related U.S. Application Data

(63) Continuation of application No. 29/648,122, filed on May 18, 2018, now Pat. No. Des. 891,384.

(57) **CLAIM**

The ornamental design for a communication module, as shown and described.

DESCRIPTION

FIG. 1 is a front perspective view of a communication module showing our new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines illustrate structure or features that form no part of the claimed design. The dash-dot-dash broken lines illustrate boundaries that form no part of the claimed design.

1 Claim, 8 Drawing Sheets
